C. LEVEN

APPARATUS FOR OBTAINING PRACTICE IN GOLF OR OTHER GAMES OR
PHYSICAL EXERCISES
Filed Oct. 17, 1921

Fig. 1. Inventor
C. Leven
By Marks Clark
A. O. T. S.

UNITED STATES PATENT OFFICE.

CHARLES LEVEN, OF LONDON, ENGLAND.

APPARATUS FOR OBTAINING PRACTICE IN GOLF OR OTHER GAMES OR PHYSICAL EXERCISES.

Application filed October 17, 1921. Serial No. 508,122.

To all whom it may concern:

Be it known that I, CHARLES LEVEN, M. I. E. E., a subject of the King of Great Britain and Ireland, and residing at 109-5 111 New Oxford Street, London, W. C. 1, England, have invented a certain new and useful Improved Apparatus for Obtaining Practice in Golf or Other Games or Physical Exercises, of which the following is a 10 specification.

The object of the present invention is to devise a form of apparatus which is primarily intended to enable the user to obtain practice in golf but which may be applied 15 with equal advantage and like effect in connection with practice in other games such as cricket, base-ball, hockey, polo and the like, or for physical games and exercises generally.

20 The invention aims at providing a form of apparatus which in addition to enabling the user to obtain the necessary practice will also afford a satisfactory indication of the state of proficiency at which he has arrived 25 and the invention consists in apparatus comprising a stick, bat or other like article or device having a weight or other member movable thereon or in connection therewith under the action of centrifugal force and 30 preferably against a suitable spring or like resistance, means being provided to maintain the weight or the like in any position which it may be forced to take up under the action of the centrifugal force so that it 35 will serve as an index of the power of the swing or other movement imparted to the device.

The accompanying drawing illustrates 40 one convenient mode of carrying out the invention in its application, for example, to a practice golf club.

Figure 1 is an elevation; and

Figure 2 is a sectional elevation.

In carrying my invention into effect in 45 one convenient manner as for example, in its application to a device intended for the obtaining of practice in golf, I form the device with an outer tubular member *a*, resembling more or less the usual driver or 50 other golf club and with the lower part of such member I provide a weight *b* which will represent approximately the head of the golf club, and which is arranged on a rod *c* within the tube and against a resist- 55 ing force such as that provided by a spring

d, elastic fluid or other resilient means or device. The arrangement is such that when the club is used in the manner of an ordinary golf club the weight will move outwards under the action of centrifugal force, the extent of such movement being 60 an index of the power of the swing.

In conjunction with such weight, I may provide a scale or index *e* which may be calibrated by calculation or by practical experiment or otherwise in terms, for example, of the length of drive or any other convenient units, and the tube is provided with a spring controlled detent *f* adapted to engage notches in the rod *c* or other member 65 on which the same is movable, or it is provided with a pawl and ratchet arrangement or with any other means or device by which it may be temporarily held in any position 70 on which the same is movable; or it is provided with a pawl and ratchet arrangement or with any other means or device by which it may be temporarily held in any position 75 which it may have been made to take up under the action of centrifugal force, thereby showing in conjunction with the scale 80 the power or skill of swing or other factor affecting the practical result that would have been attained thereby.

If desired a leather loop or other like device may be provided at that part of the stick or tube member which is gripped so that the hand of the user may be passed through such loop, thus facilitating the 85 gripping operation and serving to maintain the hold upon the stick or handle.

The head *b* may be guided in its movement by means of one or more pins *g* passing through the tubular member and 90 through a slot *h* in the rod *c*.

It is to be understood that the foregoing details and the particular application described are given by way of explanation and not of limitation as it will be clear that the 95 invention may be applied to various devices used in the playing of games or in the carrying out of physical exercises and the form of member influenced by the centrifugal force, the manner of disposing the same and the 100 means adopted for enabling it temporarily to maintain any position in which it may be set may all be modified to suit the particular purpose for which the invention is to be employed or any practical requirements that 105 may have to be fulfilled.

Having now particularly described my invention, what I claim as new and desire to secure by Letters Patent is:—

1. A swingable game piece comprising a 110

handle and a heavy head, spring responsive means associated with the head and actuatable thereby under centrifugal force during the swinging of the game piece and means to register after the stroke the power or force incident to the swing.

2. An arrangement as claimed in claim 1 wherein means is provided for releasably holding the weight actuated means in its indicating position.

3. An apparatus of the character described including in combination, a swingable game piece composed of an elongated handle portion and a head portion acting as a weight and having a graduated and notched shank, spring means associated with the shank of the head portion and actuatable by the head during the swinging of the game piece due to the centrifugal force generated to indicate the power of the swing, and means for releasably holding the parts in their indicating positions.

4. An apparatus of the character described including in combination, a swingable game piece composed of an elongated tubular handle portion and a head portion acting as a weight and provided with a graduated and notched shank slidably

mounted within the handle portion and also provided with an elongated slot, spring means associated with the shank of the head portion and actuated by the head during the swinging of the game piece due to the centrifugal force generated to indicate the power of the swing, a spring controlled catch pivoted exteriorly of the handle portion and operating through the handle portion for co-acting with the notches on the shank of the head portion for releasably holding the parts in their indicating positions, and stop means carried by the handle portion and traversing the slot in the shank of the head portion for preventing accidental displacement of the head portion during the swinging of the game piece.

5. A golf stick comprising a handle, a head slidably connected to the handle and a spring arranged between the head and handle for resisting the centrifugal force generated by the swinging stroke of the stick and means for releasably holding the head in an indicating position.

In testimony whereof I have signed my name to this specification.

CHARLES LEVEN.
